UNITED STATES PATENT OFFICE.

HENRY KÜHNE, OF RACINE, WISCONSIN.

IMPROVED STEERING AND PROPELLING APPARATUS.

Specification forming part of Letters Patent No. 35,693, dated June 24, 1862.

To all whom it may concern:

Be it known that I, HENRY KÜHNE, of Racine, in the county of Racine and State of Wisconsin, have invented a new and useful Improvement in Combined Steering and Propelling Apparatus for Vessels; and I do hereby declare that the following is a full, clear, and exact description of the same, reference being had to the accompanying drawings, forming part of this specification, in which—

Figure 1 is a side elevation of a combined propelling and steering apparatus constructed according to my invention. Fig. 2 is a horizontal section of the same.

Similar letters of reference indicate corresponding parts in both figures.

The object of this invention is to enable sailing-vessels to enter harbors without the aid of tow-boats, and to provide for the more effective steering of such vessels in intricate channels and in all waters where the navigation is difficult; and to this end it consists in a certain arrangement, in combination with a screw-propeller placed in the rudder, of a capstan and gearing for working the said propeller, and a lever for shifting the blades of the said propeller to set them at various angles or to bring them parallel with a plane passing longitudinally, centrally, and vertically through the vessel, to prevent them from dragging when it is not desired to use the propeller.

To enable others skilled in the art to make and apply my invention, I will proceed to describe its construction and operation.

A is the rudder firmly secured to an upright shaft or post, R, which is fitted to turn in suitable boxes or bearings secured to the stern of the vessel, or otherwise attached to the vessel, to allow it to turn on its axis, for the purpose of working the rudder by means of the steering-wheel B. The steering-wheel shaft C may be combined with the post or shaft of the rudder by bevel-gears D E, as shown, or by other suitable means.

F is the screw-propeller applied to the rudder, in which an opening, a a, of suitable form and size, is provided for its reception, and in which bearings are provided for the shaft b of said propeller.

G is a bevel-gear fitted to turn loosely on the shaft R, and confined between shoulders c d. This gear gears with a bevel-gear, H,

which is fast on the propeller, and a bevel-gear, I, which is fast on a horizontal shaft, J, that works in a suitable in-board bearing or bearings, e, and through a bearing, f, in the stern, the said shaft J being opposite to the propeller-shaft b, and the said gear I being arranged outside of the vessel.

K is the capstan for working the propeller F, having its upright shaft L geared by bevel-gears M N with the shaft J. The shaft J has fast upon it, outside of the vessel, a screw-propeller, P, to aid in the propulsion of the vessel; but this may be dispensed with, if thought desirable.

S is a lever for adjusting the blades h h h of the propeller F, arranged to work on a fulcrum-pin, i, which is secured in the rudder. The lower end of this lever is connected by a swivel, j, with a rod, T, which passes through the rear portion of the shaft and into the hollow hub of the propeller to connect with the inner ends of pivots formed on the propeller-blades to fit into suitable holes provided for them in the hub. The connection of the rod T with the pivots of the blades may be by means of a rack or racks on the said rod and pinions on the pivots, or by any other means that will cause the pivots and blades to be turned by the longitudinal movement of the rod, for the purpose of setting the blades at a desirable angle to the shaft b for propelling and steering, or to bring them parallel with the said shaft and with the plane of the rudder when it is not desired to use the propeller. The part of the lever above the fulcrum i is curved toward the rudder-post, that the upper end may be brought within reach of the persons on board of the vessel for the purpose of adjusting the blades.

On the vessel entering a harbor or upon the navigation of intricate channels, or on arrival in any waters or under any circumstances in which the navigation of the vessel is difficult, the propeller has its blades adjusted at a desirable angle to the propeller-shaft b, and the propeller F is set in operation by turning the capstan K, at which all hands on board not of necessity otherwise engaged may be employed. The rudder is then operated in the usual manner, and the propeller F not only acts to propel and keep steerage-way on the vessel, but in the steering of the vessel by the ordinary opera-

tion of the rudder it acts very effectively in exerting its propelling power to bring round the stern of the vessel in the desired direction, and so assist in steering the gear G by rotating about the axis of motion of the rudder, permitting the free movement of the rudder while transmitting motion from the gear I on the shaft J to the gear H on the propeller-shaft.

I do not claim the employment of a screw-propeller arranged within the rudder of a steam-vessel, nor do I claim of itself making a screw-propeller with adjustable blades; but

What I claim as my invention, and desire to secure by Letters Patent, is—

The combination of the screw-propeller F, arranged in the rudder, and having adjustable blades, the capstan K, shafts L J, gearing M N I G H, and lever S, the whole applied and arranged substantially as herein set forth.

HENRY KÜHNE.
